AND WILLIAM G. CLARK, OF SAME PLACE.

PAPER-BAG MACHINE.

SPECIFICATION forming part of Letters Patent No. 644,130, dated February 27, 1900.

Application filed July 29, 1899. Serial No. 725,469. (No model.)

To all whom it may concern:

Be it known that we, JAMES W. DUVALL and GEORGE A. SHEPARD, of Middletown, Butler county, Ohio, have invented certain new and useful Improvements in Paper-Bag Machines, of which the following is a specification.

This invention, pertaining to paper-bag machines, has reference to that portion of the machinery dealing with a bellows-folded paper tube and serving to form the diamond fold in the bottom of the bag-sections of the tube and leave the bottom in condition to have paste applied and then have its flaps folded to complete the bottom.

Our machine operates upon connected blank-sections; and it consists of a roll having a pair of side grippers and a flap-holder, a cylinder running in connection with and having a diameter in multiple of that of the roll, a multiplicity of pairs of side grippers carried by said cylinder, means for operating the grippers carried by the roll, means for operating the grippers carried by the cylinder and holding said grippers in engagement with the blank until after the succeeding pair of grippers has engaged the next blank-section, and mechanism for turning said roll and cylinder continuously forward. This construction enables us to pass the connected bag-sections between the roll and cylinder, which act as their own feeders, and to discharge the same in a string of bag-sections, with diamond folds produced in each section.

Our invention will be readily understood from the following description, taken in connection with the accompanying drawings, in which—

Figure 1 is a side elevation of a machine exemplifying our invention; Fig. 2, a plan of the same; Fig. 3, an enlarged side elevation of the coacting portions of the roller and cylinder, certain fixed cams appearing in vertical section in the plane of line *a* of Figs. 2 and 4; Fig. 4, a plan of one of the grippers; Fig. 5, a plan of an illustrative bellows-folded tube, showing the bag in various stages of progress, the seamed side of the tube being uppermost; and Fig. 6, a bottom view of the same tube—that is to say, the seam being underneath.

In the drawings, and referring now only to Figs. 5 and 6, 1 indicates a bellows-folded paper tube of the usual form employed in bag-making; 2, the usual seam thereof, which seam we prefer shall be on the uppermost side 55 of the tube as it is fed to our machine; 3, short curved cross-slits cut through the lower ply of the tube at a distance apart represented by the length of each bag-section; 4, cross-slits cut through both plies of the bellows fold, 60 their inner extremities joining the outer extremities of curved cross-cuts 3, whereby the tube as thus far provided with cross-cuts is completely severed in its lower ply and severed at the upper ply, except as to that portion 65 represented by the length of the curved cross-cuts 3; 5, the tails which thus form the connection between the bag-sections after the cross-cuts 3 and 4 have been made, these tails serving as means by which the tube and the 70 bag-sections in various steps of completion are drawn through the machine, it being understood that the tube, as represented by Figs. 5 and 6, moves to the right in passing through the machine; 6, the notches formed in the rear 75 end of the lower ply of each bag-section by the cutting of curved cross-cuts 3, these notches forming the finger-notches in the mouths of the completed bags; 7, a portion of the tube of bag-section length comprehended between the 80 curved cross-cuts 3 and the set of undisturbed cross-cuts 4, this portion 7 of the tube representing a bag-section at the first stage of action of our machine; 8, a portion of the tube just in advance of portion 7 and representing a bag- 85 section in the second and final stage of action of the machine, the diamond fold having been formed in the bottom of the bag-section, ready for the application of the paste and the folding of the flaps of the diamond; 9, a portion 90 of the tube in advance of portion 8 and representing the bag-section as having had its bottom pasted and its flaps folded, leaving the bag completed and ready to be completely severed from portion 8; 10, the side members 95 of the diamond fold or portion 8 of the tube ready for the reception of the bottom paste; 11, the prow-flap of the diamond fold ready to be folded back and pressed down to the bottom as soon as the bottom paste shall have 100

been applied and tail 5 shall have been severed from the completed bag-section; 12, the trailing flap of the diamond fold, ready to be folded forward and pasted to the bottom as soon as the bottom paste shall have been applied, and 13 the completed bottom of the paper bag after the flaps have been folded and pressed.

Our machine receives the bellows-folded tube provided with the curved cross-cuts 3 and produces the cross-cuts 4 and then forms the diamond fold, thus putting the bag-section into the condition indicated by portion 8 of Figs. 5 and 6, ready for the usual operation of applying the bottom paste and folding the prow and trailing flaps of the bottom, the diamond fold being formed upon the given bag-section while the preceding bag-section is still attached to it by the tail 5. The series of bag-sections, with the diamond fold formed at each section by the action of our machine, may then be subjected to the action of other and usual mechanism for pasting and folding the flaps, or, if desired, such mechanism may be added to our machine, which in its preferred construction has its diamond-folded bag-sections carried forward by a revolving cylinder such as is frequently employed in connection with mechanism for applying paste to and folding the flaps of diamond-folded bag-sections.

The duty of our machine having been explained in connection with Figs. 5 and 6, we will now describe the preferred construction and the mode of operation of the same.

Referring to the remaining figures of the drawings, 14 indicates a roll having a measure of circumference represented by the length of the desired bag-section and having a length somewhat in excess of the width of the bellows-folded tube to be dealt with, it being understood that, looking at Figs. 1, 2, and 3, the bellows-folded tube provided with curved cross-cuts in its lower ply comes to our machine from the left and engages the upper and right-hand portions of the periphery of roll 14; 15, fixed frame parts of the machine; 16, a pair of gripper-spindles, one mounted at each end of roll 14, the axes of these spindles being parallel with each other and at right angles to the axis of roll 14; 17, a gripper-finger projecting from each of the gripper-spindles and adapted when turned inwardly toward each other to lie snugly upon the periphery of roll 14, these fingers when thus swung inwardly lying upon the periphery of roll 14 in angular lines, their points converging rearwardly as the roll turns in the direction of the arrow, the angle of convergence being that represented by the usual breaking lines of the inner plies of the bellows at the diamond fold, as indicated by dotted lines 31 in Fig. 5, fingers 17 when swung outward out of action being clear of the roll, as indicated in Fig. 2; 18, ball-bearings for the gripper-spindle 16; 19, an arm projecting outwardly from each gripper-spindle 16, sub-

stantially at right angles with its finger 17, the outer end of the arm being preferably provided with an antifriction-roll, as indicated; 20, fixed cams supported by the framework at each end of roll 14 and adapted as the roll turns forward to be engaged by arms 19 and serve in swinging the fingers 17 inward to active position on the periphery of roll 14; 21, a spring at each of arms 19, serving to hold its finger 17 to outward inactive position, but to permit the finger to swing inwardly under the influence of its cam 20; 22, a pair of spurs projecting from the periphery of roll 14 at such distance apart as to engage that portion of the lower ply of the tube which is cut from notch 6 and forms the foremost portion of the bag-section before the diamond is formed and the tag of the trailing flap after the diamond is formed, the spurs 22 being disposed on roller 14 in advance of the finger 17 a distance appropriate to the distance between the part of the tube engaged by the spurs and the breaking line of the inner plies of the bellows folds; 23, a cross-cutting blade carried by the periphery of roll 14 to the rear of spurs 22 in position to make the cross-cuts 4 illustrated in Fig. 5; 24, a fixed stripping-finger engaging a peripheral groove in roll 14 and adapted at the proper time to strip the tag of the trailing flap from spurs 22; 25, a roll mounted in the framing and having its periphery running in contact with that of roll 14, roll 25 having three times the diameter of roll 14 and being hereinafter termed the "cylinder" or "carrier;" 26, three pairs of grippers, similar to those described in connection with roll 14, mounted on cylinder 25, the pairs being equally spaced apart upon the periphery of the cylinder, so that the peripheral distance between the pairs of grippers equals the length of the given bag-section and equals the circumference of roll 14, the angular relationship of the roll to the cylinder being such that the pair of grippers on the roll will exactly match a pair of grippers on the cylinder as the four grippers pass the line of contact between the roll and the cylinder; 27, fixed cams, one at each end of the cylinder and adapted as the cylinder turns to engage the operating-arms of the grippers on the cylinder and throw those grippers inwardly to active position at the same instant cam 20 causes gripper-fingers 17 to go into active position; 28, intermeshing gears on the shafts of the roll and the cylinder, their pitch diameters being equal to the diameters of the roll and cylinder, respectively; 29, a pulley on the shaft of roll 14 and serving to exemplify means by which operative motion is given to the parts; 30, a press-roll mounted in the framing and having its periphery running in contact with that of the cylinder some distance in advance of roll 14, and 31, Fig. 5, the dotted lines herefore referred to as indicating the breaking-lines of the inner plies of the bellows fold as the bottom is opened to form the diamond fold.

Referring to Fig. 3, spurs 22 coöperate with suitable clearance-holes in cylinder 25, as is usual in connection with spurs provided upon one of a pair of coöperating rolls, and similarly cutting-blade 23 coöperates with suitable cross-notches in cylinder 25.

Turning to Fig. 1, the bellows-folded tube, provided with the curved cross-cuts 3 in its lower ply, comes to the machine from the left, 10 passing over the top of roll 14 and down between roll 14 and cylinder 25 and then, generally speaking, on around under cylinder 25, being held thereto by the tails connecting the bag-sections and by such of grippers 26 as 15 have passed roll 14 and not yet been released. As thus considered the tube would be fed between the roll and the cylinder and be carried around under the cylinder until released therefrom by grippers 26 reaching the terminals of cams 27.

During the progress of the tube through the machine as a curved cross-cut 3 comes in line with the line of contact between the roll and the cylinder cross-cut blade 23 produces the 20 cross-cuts 4, thus entirely severing the tube into bag-sections, except as the bag-sections are united by the tails 5 in the upper ply. As thus far considered the tube would pass through the machine and be severed into bag- 25 sections, except as to the connecting-tails 5, the series of bag-sections being carried by the cylinder until released when grippers 26 reach the terminals of cams 27; but at the instant cross-cuts 4 are made and the line of those 30 cuts is passing the contact-line between the roll and the cylinder the spurs 22 penetrate the prow of the lower ply of the tube and as the roll and cylinder continue to rotate draw the lower ply of the bag-bottom to the surface 35

40 of roll 14 and cause the lower ply to accompany the periphery of roll 14, while the upper ply of the tube accompanies the periphery of the cylinder, the effect being to drag open the bottom of the bag. An early effect of this 45 opening of the bottom is of course to open the bellows folds, and as grippers 17 and 26 slightly pass the line of contact between the roll and the cylinder the bellows folds are opened sufficiently to permit these grippers 50 to properly enter. At this time the arms 19 of the grippers engage the cams 20 and 27, whereby the fingers of the grippers 17 and 26 are caused to swing inwardly and clamp the two lower plies of the bellows fold to the roll 55 and the two upper plies of the bellows fold to the cylinder, the clamping taking place on the breaking-lines represented by dotted lines 31 in Fig. 5. The result is that as the bottom of the bag continues to be dragged open the 60 bellows folds break on lines 31, thus producing the diamond fold, as the opening motion produces a flattening of the bag-bottom somewhat at right angles to the general plane of the tube. As the roll and cylinder continue 65 to turn the time will soon come when the bag-bottom has been stretched to its utmost by the strain of spurs 22 pulling the trailing

flap of the bottom away from the prow-flap carried onward by the cylinder. When this time arrives, any further opening of the bag- 70 bottom can result only in tearing the paper.

At this instant the stripper 24 strips the trailing flap from spurs 22, thus releasing the trailing flap from the roll, and at about the same time the terminals of cams 20 are 75 reached by arms 19, whereby fingers 17 move outwardly to inactive position, thus entirely releasing the diamond-folded bag-bottom from roll 14, leaving the bag-bottom still held to the cylinder by the tail which unites the 80 bag-sections and by cylinder-grips 26, which are still in action. The bag-section, with its diamond fold thus formed, is carried forward by the cylinder, and the folds of the diamond are pressed by roll 30, thus completing the action of our improvement and leaving the bag-section in condition to receive the bottom paste and have the flaps folded and pressed by the usual mechanism, which, if desired, may operate in conjunction with 90 that portion of cylinder 25 beyond press-roll 30, cams 27 being prolonged, so that the cylinder retains its grip upon the bag-sections until the bottom paste has been applied, the trailing flap folded and pressed, the tail at the 95 prow-flap severed from the preceding bag, the prow-flap folded and pressed, and the bag thus completed severed from the succeeding bag-section and ready for final discharge.

We should, perhaps, explain that it is preferable that the tube as it enters our machine be provided with the usual creases where the folds of the diamonds are to take place, it being understood that this creasing may be formed as usual and by the usual creasing 100 mechanism.

It has been proposed by numerous inventors to form the diamond fold at the bottom end of paper-tube sections by means of a cylinder operating in conjunction with a folding-plate, 110 the latter having very complicated motions. It has also been proposed by numerous inventors to form the diamond fold by means of a pair of coöperating cylinders carrying various forms of folding devices and having 115 more or less complicated adjuncts and movements; but in these latter cases the rolls have had to deal with both flaps of the bottom end of the bag-section, and it thus became necessary to feed the bag-section to exact position between the cylinders and then cause both of the flaps of the bag-section to be engaged either by flap-grippers centrally disposed upon the cylinder or by extraneous flap-gripping agents. So far as we are apprised 120 of the state of the art we are the first to subject a paper tube to the action of a simple pair of cylinders running in contact with each other and having a simple continuous forward motion and by means of these simple 125 cylinders and side grippers carried by them form the diamond folds without the necessity for the employment of flap-grippers upon both cylinders or extraneous devices for engaging 130

the flaps during the operation of the cylinders in forming the diamond fold.

We claim as our invention—

In a paper-bag machine for operating upon connected blank-sections, the combination of a roll, a pair of side grippers carried thereby, a flap-holder carried by said roll; a cylinder running in contact with and having a diameter in multiple of that of the roll, a multiplicity of pairs of side grippers carried by said cylinder, means for operating the grippers carried by the roll, means for operating

the grippers carried by the cylinder, and holding said grippers in engagement with the blank until after the succeeding pair of grippers has engaged the next blank-section, and mechanism for turning said roll and cylinder continuously forward. 15
